UNITED STATES PATENT OFFICE.

HORACE JOHN HOWARD, OF BRISTOL, ENGLAND.

VALVE MECHANISM FOR INTERNAL-COMBUSTION ENGINES.

Application filed December 26, 1918. Serial No. 268,376.

To all whom it may concern:

Be it known that I, HORACE JOHN HOWARD, a subject of the King of Great Britain, and a resident of 59 Filton Avenue, 5 Gloucester Road, Bristol, England, have invented an Improved Valve Mechanism for Internal-Combustion Engines, of which the following is the specification:—

The main object of this invention is to 10 provide in an internal combustion engine a light slide valve so arranged with relation to its actuating cam that the valve is actuated directly without any intervening mechanism.

Another object is to provide a construction and arrangement forming a compact combustion chamber containing in combination a detachable recessed head, a slide valve and its actuating cam, and a driving gear wheel. A further object is to provide a valve 20 member that shall be extensible radially yet non-elastic, that shall be without pockets or projections in the combustion chamber, and light enough for the most rapid actuation.

Referring to the accompanying drawings:—

Fig. 1 is a sectional elevation of a complete assembled unit showing the various component parts in their respective positions, with the valve in its central and closed 30 position;

Fig. 2 shews the valve separately, and

Fig. 3 shews the cylinder head with the rotary grooved cam and packing ring in position.

The upper portion of the cylinder containing the valve and its actuating cam is 35 preferably made in one piece with the working cylinder; the barrel portion 1, Fig. 1, is inserted through two walls formed in an upwardly extended portion of the crank case, not shown, the space between the two walls containing the cooling water. This construction is to obviate an explosion joint in the combustion chamber, for the cylinder being

40 inserted up to the shoulder 4 it remains permanently fixed, and would only need removing in case of breakage for the insertion of a fresh unit. The utmost accessibility is given to the combustion chamber by the employment of a deeply recessed readily detachable head, Fig. 3, this head having to resist the explosion pressure the holding down bolts make an effective explosion joint with the cylinder head.

45 The described construction with insertable cylinder is equally suitable for engines with

cylinders in line as well as for those whose cylinders are arranged in a circle round a cam driving shaft with their axes parallel to the same. In both these formations the 50 adjacent sides of the outer end of the cylinders are machined to fit snugly together.

The gas ports 2 and 3 are arranged one above the other in two annular rows, the top row 2 being preferably used for exhaust, 55 and the inner or lower row 3 for the inlet. These ports are covered by the inner or lower end of the tubular slide valve, shown by Fig. 2, the ring of ports 7 cut through this valve is adapted to register with the cylinder ports, 60 so that a movement of the valve in an upward direction uncovers the exhaust ports 2, and in a downward direction the inlet ports 3, thus both the exhaust and inlet gases pass through the same valve ports, equalizing the 65 temperature of the port edges. During the working and compression strokes the ports 7 are shown in Fig. 1 in the mid position between the inlet and exhaust ports. The tubular slide valve 6 is contained partly in 70 the combustion chamber over the ports, and partly in an annulus formed between the upper part of the cylinder and a deeply recessed head 8 which closes the combustion chamber, the lower edge of the head being 75 coincident with the exhaust ports outside the slide valve.

Instead of the annular ports shown, it may be necessary in some cases to form the exhaust ports on one side of the cylinder and 80 the inlet on the other, in these cases two ports would be cut one above the other in parallel relation in the valve to register with similar ports in the cylinder wall, the lower edge of the valve may be used on one side to uncover 85 a port at the same time as the valve port above it is uncovered. This double porting is only necessary in high speed engines where large port area with a short valve travel is essential.

The recessed head can carry one, two or 90 three packing rings to seal the combustion chamber against gas leakage between the head and the tubular valve which it fits within. It is however preferred to use a broad 95 split packing ring 9 having its split edges tongued together by square teeth 11, Fig. 3, these teeth preventing the upward escape of gas providing both sides of the teeth are similarly sealed. The outside is naturally 100 sealed by pressing against the valve member, and to prevent the passage of gas up the 105

back of the teeth a spring pressed sector piece 12 is used fitting the curvature of the ring and also the ring groove. In a modification a complete spring ring may be used 5 instead of the sector piece, fitting within the outer ring and also the ring groove, but with its joint well away from the outer ring joint.

The upper part of the head carries in a 10 suitable recess or annulus the cam 13 for operating the valve. This cam is formed as a grooved ring, the cam being rotated within the valve member having the cam groove on its outer surface shaped to give the desired motion to the valve member which it operates by connecting pins 15 projecting from the valve, and running in the cam groove 14. The cam groove being of relatively 15 large diameter the cam has its speed of rotation reduced and two pins 15 are fitted one on each side of the groove. The cam groove 20 contains two four stroke cycles to effect the necessary strokes, compression, explosion, exhaust and inlet in sequence.

As the projecting pins 15 cannot be fitted 25 with rollers advantageously to reduce friction in the cam groove, it is preferred to employ a hardened detachable pin to connect the cam to each valve member to operate the valve.

30 To use antifriction means with advantage, the cam should take the form of a projecting rib or flange having a roller on each side of same.

Rotary motion is imparted to the cam ring 35 by means of a toothed ring 16 attached to or formed integrally with the cam ring. This gear wheel is driven in any suitable manner, as for example by a gear wheel on a vertical shaft driven by the crank shaft, not 40 shown. Or it may be driven by worm or skew gearing by a horizontally mounted shaft along the cylinder heads. When a plurality of cylinders provided with this sleeve valve and cam are employed the said gear wheels may be driven by the gear wheel 45 in the adjacent cylinder.

The cam ring is arranged in the recessed head as shown in Fig. 3, within the valve, but it can be arranged to revolve in an 50 annulus formed between the outside of the valve and an enlargement of the cylinder bore. In the method shown the recessed head is formed in two parts 8 and 19, screwed together to enable the cam ring to be assembled.

As the cam is rotated round the cylinder axis, and the valve is required to move parallel to that axis, it follows that means must be provided to prevent the valve moving in 55 any but an axial direction, and though not limited to this particular method, it is conveniently done by forming the heads of the projecting pins 15 as keys 17 which travel in keyways 18 cut either in the cylinder wall or in the cylinder head on the opposite

side to the projecting actuating pin, to suit either an inside or an outside cam. The actuating pins 15 are formed in one piece with the key 17 and hardened, the pins are a tight fit in the valve member to which 70 they are attached by a rivet or screw.

For the reason previously explained, two or more cycles are completed in one revolution of the cam, it follows therefore that the cam groove must be symmetrical, also the 75 actuating pins 15 projecting from the valve surface must engage freely in this groove, and be equally spaced and guided so that the valve pins receive their motion in perfect unison with each other during the revolution of the cam ring.

To operate a single split ring valve by this method with more than one operating pin, this invention proposes to fix and retain the equal spacing of the operating pins 85 by keyways 18 cut in the valve housing, and allowing all expansion and wear to adjust itself between these points. This is accomplished by making the tubular valve in two parts as shown in Fig. 2, and joining the adjacent edges as shown by square tongues 10 and recesses that lock together to form a complete tube expandible yet non-elastic. In larger engines the valve may 90 be divided longitudinally into three parts 95 instead of two.

A modification of the axially revolving cam would be to use only one side of the groove cam by means of a roller on the valve member kept in close contact therewith by spring pressure applied to the valve member from above preferably at the guiding keyways 18, thus the valve will be operated in one direction by the cam and in the return direction by the spring. 100

It is known to key the edges of a split ring valve to prevent axial distortion of the valve edges, but the present invention uses this method to prevent gas leakage past the joints of a valve member that is open to the atmosphere at its outer end, to allow of its ready assembly on its cam groove, to give it expansibility without initial springing, and to facilitate its manufacture. 105

It is important that all the working surfaces of the valve and the packing ring overrun the corresponding working surfaces on the cylinder and the valve to prevent the edges of these parts being rounded, or wearing a ridge in the cylinder or valve at the end of their travel. The cylinder is recessed or grooved as at 20, Fig. 1, a similar recess is formed on the inside valve surface a little before the end of the stroke, so that 110 the edges of the packing ring 9 overrun the working surface inside the valve, with the same object. 115

To effectively lubricate the various parts, the valve and cam are perforated with 120 125 130

holes, to facilitate the free flow of lubricant to all working faces. These parts not being within the combustion chamber oil applied to the driving teeth can readily spread to the parts requiring lubrication.

In Fig. 1, the ignition plug opening is shown situate in the recessed head with a gas cooling duct leading to it, and this is the preferred construction, but it may be 10 situate on one side of the engine between the cylinder ports, and opening into the valve port when the latter is in its central closed position, which arrangement provides that the ignition passage is only 15 opened during the compression and firing strokes.

What I do claim as my invention and desire to secure by Letters Patent is:—

1. In an internal combustion engine, a 20 cylinder having inlet and exhaust ports, a sectional sleeve valve reciprocable within the cylinder head to control the inlet and exhaust ports, each of said sections being formed along their longitudinal edges with 25 alternating teeth and recesses, the teeth on one section fitting the recesses of the other section, and means for operating the valve.

2. In an internal combustion engine, a cylinder having inlet and exhaust ports, a

sectional expandible sleeve valve reciprocable 30 in the cylinder for controlling the inlet and exhaust ports, a cam rotatably mounted in the cylinder and projections carried by the sleeve valve and engaging the cam.

3. In an internal combustion engine, a 35 cylinder having inlet and exhaust ports and vertically extending guideways therein, a sleeve valve reciprocable in the cylinder for controlling the inlet and exhaust ports, a cam rotatably mounted in the cylinder, keys 40 secured to the valve and operating in the guideways, projections formed on the keys and extending through the valve and engaging the cam, and means for rotating the cam.

4. In an internal combustion engine, a cylindrical slide valve adapted to reciprocate over ports formed in the wall of the combustion chamber by means of an annular cam arranged and rotated in the cylinder head in such a manner that its axis is coincident with or parallel to the valve axis, said slide valve being formed of two semicircular portions, each being formed with alternate teeth and recesses, the teeth 55 of the one part fitting the recesses of the other part for the purpose set forth.

HORACE JOHN HOWARD.
